UNITED STATES PATENT OFFICE.

JOSEPH C. ATKIN, OF SAN FRANCISCO, CALIFORNIA.

GAME.

Application filed February 20, 1920. Serial No. 360,061.

To all whom it may concern:

Be it known that I, JOSEPH C. ATKIN, a subject of Great Britain, residing in the city and county of San Francisco, State of California, have invented certain new and useful Improvements in Games, whereof the following is a specification.

This invention relates to games, especially parlor games, and it comprises a game board, and support therefor, and a game to be played thereon.

The object is to provide a simple and cheap apparatus and an interesting game which shall require some skill to play it.

In carrying out the invention I provide a target with a series of thirteen hooks thereon, said hooks numbered in a certain order. The target is preferably circular in shape and supported upon an easel having three legs, which are self engaging and self fastening and have only to be applied to one another in proper position to engage and retain their position. The game includes also a number of rings. Each player, of whom there may be any number, shall stand about eight feet from the board and shall pitch six rings, endeavoring to have the rings engage the hooks in the numerical order of the latter. For example, if a player trying to get hook number 3, gets some other number, that number does not count. The winner is the one who first gets the thirteen hooks.

The board and hooks may also be used for the card game of cribbage, instead of cards. Used this way, the players score all the fifteens possible, score all the runs possible. Five rings diagonally across the board may be the equivalent of a flush and count five points. The one may count as his "nobs."

Other games may be played, as for example one which may be called "High score," in which all numbers count, and the object is make the highest score, up to, say, one hundred.

In the accompanying one sheet of drawing I have illustrated my invention in its best form, in six figures, of which:—

50 Figure 1 is a front elevation, showing the target on the easel, with some of the rings engaged upon the hooks.

Figure 2 is a side elevation of the same.

Figure 3 is a rear elevation of the upper 55 part of the easel, showing how the back leg

engages the two side legs and holds them together.

Figure 4 shows the upper part of the two side legs of the easel separated, and shows the studs and sockets by which they engage 60 and the eyes for the engagement of the back leg.

Figure 5 is a front, or rear, elevation of the back leg, showing the fork to engage the eyes of the side legs.

Figure 6 is a side elevation of the same.

In the figures:—The target A is provided with thirteen hooks, circularly arranged thereon and numbered as shown, there being one hook, 13, in the middle, a hook near the circumference on each of the eight radial lines, to wit: 1, 2, 3, 4, 5, 6, 11 and 12, and four hooks on the four diagonal lines intermediate the center and circumference, to wit: 7, 8, 9 and 10.

The rings B are shown as hung upon the hook. These may be of any material, and be plain or ornamental, and round or of other shape. Their number is immaterial, but I contemplate the use of six by each 80 player, and there may be any number of players.

The target A is supported by the easel, by resting upon the hooks or studs C in the fronts of the side legs D and E, and the hooks F secured to the legs engaging the rings G (only one being shown) in the back of the target.

The side legs of the target engage by means of studs H entering sockets I shown in dotted lines, the studs being on one leg and the sockets in the other, at the meeting tops thereof. The engagement is ensured and maintained by means of two eyes K on the back of the legs, into which enter the 90 prongs L of the fork M at the top of the rear leg N. The prongs L flare outward slightly to draw and lock the tops of legs D and E together. A long hook bar O engaging the eyes P and Q on the side legs D and E near the lower ends thereof, maintain 95 their proper spacing at that point.

The fork M has a flat surface R at an angle with the leg N to bear against the legs D, E, and gauge the slant of the rear member.

Having thus described my invention, and an embodiment of it, in the full, clear and exact terms required by law, and knowing that it comprises novel, useful and valua- 110

able improvements in the art to which it pertains, I here state that I do not wish to be limited to the precise construction and arrangements of the several parts, as herein set forth, as the same may be variously modified by a skilled mechanic without departing from the spirit of the invention.

What I claim and desire to secure by Letters Patent of the United States, is the following, to wit:

1. As an article of manufacture, a game board comprising a vertical stationary target made of one piece of material and of a circular shape, hooks circularly disposed upon said target, one of said hooks being centrally located, eight hooks secured near its circular edge and four intermediate hooks on its oblique radii, in combination with rings adapted to be thrown by the players to engage said hooks, an easel provided with studs for removably supporting said target above the floor and hooks on said easel engaging rings on said target adapted

to hold firmly said target in a vertical position.

2. As an article of manufacture a game board comprising a vertical stationary target of a circular shape having a plurality of hooks circularly arranged thereon, each hook being of a different permanent denomination, one of said hooks being located in the center of said target and marked 13, eight hooks near its circular edge marked 1, 2, 3, 4, 5, 6, 11 and 12, and four intermediate hooks on its oblique radii marked 7, 8, 9 and 10, in combination with rings adapted to engage said hooks and removable legs provided with studs for supporting said target thereon and hooks on said legs engaging rings on said target adapted to hold said target in a vertical position.

In testimony that I claim the foregoing, I have hereto set my hand this 14th day of February, 1920.

JOSEPH C. ATKIN.
